C. M. YATES.
CONDENSER.
FILED JUNE 3, 1921.

FIG. 2.

FIG. 1.

FIG. 3. FIG. 4.

INVENTOR-

Charles M. Yates.

UNITED STATES PATENT OFFICE.

CHARLES M. YATES, OF JACKSON, TENNESSEE.

CONDENSER.

Application filed June 3, 1921. Serial No. 474,847.

To all whom it may concern:

Be it known that I, CHARLES M. YATES, a citizen of the United States, residing at Jackson, in the county of Madison and 5 State of Tennessee, have invented new and useful Improvements in Condensers, of which the following is a specification.

My invention relates generally to improvements in the construction and operation of condensing apparatus, and relates more specifically to improvements in condensers of the type wherein steam is condensed by virtue of being conducted in direct contact with a plurality of jets of cooling water.

A general object of my invention is to provide a condenser which is simple in construction and efficient in operation.

A more specific object of the invention is 20 to produce a jet condenser in which the condensing agency or cooling water is uniformly distributed throughout the condensing zone, thus effecting rapid and efficient condensation of the steam. Another specific object is to provide a relatively compact 25 jet condenser of large capacity which is adapted to maintain relatively uniform high vacuum throughout considerable variation in range of operating conditions. A further specific object is to provide condensing 30 apparatus which may be manufactured at minimum cost and the design of which may be readily altered to conform with the desired conditions of operation. These and other objects of the invention and the manner in which they are attained, will be apparent from the following description.

A clear conception of an embodiment of 40 my invention may be had by referring to the drawing accompanying and forming a part of this specification, in which like reference characters designate the same or similar parts in the various views.

Fig. 1 is a central vertical section through 45 a jet condenser embodying the improvement.

Fig. 2 is a top part sectional view of a jet condenser of the type disclosed in Fig. 1, the section being taken on the line II—II of Fig. 1.

50 Fig. 3 is an enlarged side elevation of one of the stream splitters.

Fig. 4 is an enlarged rear view of one of the stream splitters.

Fig. 5 is an enlarged bottom view of one of the stream splitters.

The jet condenser illustrated complete in Figs. 1 and 2, consists generally of a main casing having a steam inlet or supply conduit 2 communicating with the upper end thereof, a cooling water inlet or supply conduit 6 leading into the side of the casing near its top, an air outlet or discharge conduit 9 leading from the side of the casing at its upper extremity, and a water outlet or discharge conduit 7 leading from the lower side portion of the casing. The main casing comprises an upper section 16, an intermediate section 17 and a lower or base section 18, these sections being detachably connected in order to permit dismantling and assembly of the structure.

The upper casing section 16 is provided with a central annular wall which forms a condensing zone 3 and which is penetrated by a plurality of rectangular water injection orifices 14 directed inwardly toward the center of the condensing zone 3. Depending from the lower end of the central upper casing section wall, is an annular downwardly converging wall 4 which forms a constriction at the lower end of the condensing zone 3. The central annular wall of the casing section 16 is surrounded by two annular chambers 10, 12 which are segregated from each other by suitable partition walls. The annular water supply chamber 10 establishes communication between the cooling water inlet conduit 6 and all of the injection orifices 14; while the annular air chamber 12 establishes communication between the annular air collecting pocket 11 which surrounds the depending wall 4, and the air outlet conduit 9. A vacuum breaker connection 13 communicates with the water inlet conduit 6 and connects with a vacuum breaker of suitable construction.

A stream splitter 15, shown in detail in Figs. 3, 4 and 5, is secured to the annular inner wall of the upper casing section 16 above each of the water injection orifices 14. Each of the stream splitters 15 has a jet dividing and spreading member 19 ex-

tending downwardly and centrally across the adjacent orifice 14. The splitter members 19 are formed wedge shape to enable them to cut the jets, and may be located at 5 any desired distance in front of the injection orifices 14.

The intermediate casing section 17 supports the upper section 16 and rests upon the base section 18. The water collecting 10 chamber 5 located within the intermediate casing section 17 communicates with the condensing zone 3 through the passage formed by the converging wall 4, and has free upward communication with the air chamber 12 through the annular air pocket 11. One or more pumps 8 mounted within the intermediate casing section 17, are adapted to remove the mixture of water of condensation and cooling water from the chamber 20 5 and to deliver this mixture from the condenser through the water discharge conduit 7. The casing section 17 may be provided with one or more manholes for permitting ready inspection of the interior of 25 the condenser.

During normal operation of the apparatus, steam is admitted downwardly into the condensing zone 3 through the steam supply conduit 2. Cooling water is admitted to the 30 annular chamber 10 from the supply conduit 6 and is delivered from the chamber 10 into the condensing zone 3 through the orifices 14 in the form of rectangular solid jets, the velocity of the jets thus delivered from the 35 orifices 14 being dependent upon the pressure maintained in the chamber 10. As each of these jets strikes the adjacent splitter member 19, it is divided into two parts which are forced horizontally away from 40 each other, and each of which is spread laterally to produce a film of liquid disposed vertically within the condensing zone. The downwardly advancing steam flows along and in direct contact with both side surfaces 45 of each of these jet films, and is quickly condensed. Due to the provision of superposed orifices 14, the steam which is not condensed by contact with the upper row of jet films, eventually impinges against the lower row of 50 jet films, thereby insuring complete condensation of the steam within the condensing zone 3. The mixture of air, water of condensation and cooling water is delivered from the condensing zone 3 into the chamber 5, through the constriction produced by the 55 annular wall 4. In the chamber 5, the air which escapes from the mixture, rises into the annular air pocket 11 from which it is withdrawn through the chamber 12 and the 60 outlet conduit 9 with the aid of a suitable ejector or pump. The water delivered into the chamber 5 is discharged through the outlet conduit 7 by means of the pumps 8, thus providing for continuous and rapid con-

densing of the steam admitted to the condenser through the conduit 2.

It may in some instances be desirable to increase or diminish the number and the size of the orifices 14 and also to stagger them vertically, but this is a detail of construction which forms no part of my present invention. It will also be obvious that the location and shape of the stream splitters 15 is an important factor in securing proper location, shape and distribution of the water 75 films, and it is therefore not intended to limit the invention to the exact details of the embodiment herein illustrated.

By locating the air discharge conduit in communication with the highest portion of 80 the main casing, and providing suitable communication thereto, undesirable pocketing of air is entirely eliminated and maximum vacuum conditions are maintainable. The location of the vacuum breaker connection 85 13 as illustrated, also insures efficient operation of the condenser without introducing danger of injury to machinery associated with the apparatus, due to excessive accumulation of water in the condenser.

It should be generally understood that I do not desire to be limited to the exact details of construction herein shown and described, for obvious modifications may occur to persons skilled in the art.

I claim:

1. In combination, a casing forming a condensing zone, means for delivering a solid jet of cooling water into said zone, means for laterally spreading said jet to 100 form a film of water within said zone, means for delivering steam against said film of water, and means for conducting fluid from said zone.

2. In combination, a casing forming a 105 condensing zone, means for delivering a solid jet of cooling water into said zone, means for dividing said jet and for laterally spreading the divisions thereof to form 110 films of water within said zone, means for delivering steam against said film of water, and means for conducting fluid from said zone.

3. In combination, a casing forming a condensing zone, means for delivering a 115 solid jet of cooling water into said zone, a splitter in the path of said jet for dividing the same and for laterally spreading the divisions thereof within said zone, means for delivering steam against said jet divisions, 120 and means for conducting fluid from said zone.

4. In combination, a casing forming a condensing zone, means for delivering a solid jet of cooling water horizontally into 125 said zone, means for laterally spreading said jet to form a vertical film of water within said zone, means for admitting steam to an

upper portion of said zone, and means for conducting fluid from a lower portion of said zone.

5. In combination, a casing forming a condensing zone, means for delivering a solid jet of cooling water horizontally into said zone, means for dividing said jet and for laterally spreading the divisions thereof to form vertical films of water within said zone, means for delivering steam downwardly along said films of water, and means for conducting fluid from a lower portion of said zone.

6. In combination, a casing forming a condensing zone, means for delivering a solid jet of cooling water horizontally into and toward the center of said zone, means for vertically dividing said jet and for laterally spreading the divisions thereof to form vertical films of water within said zone, means for conducting steam downwardly through said zone and along said films of water, and a downwardly converging wall for conducting fluid from the lower end of said zone.

7. In combination, a casing forming a condensing zone, means for delivering a solid jet of cooling water horizontally into said zone, a vertical splitter in the path of said jet for dividing the same and for laterally spreading the divisions thereof within said zone, means for conducting steam downwardly through said zone and against said jet divisions, and a downwardly converging wall for conducting fluid from a lower portion of said zone.

8. In combination, a casing forming a condensing zone, means for delivering an annular series of solid jets of cooling water into said zone, means for laterally spreading each of said jets to form films of water within said zone, means for delivering steam against said films of water, and means for conducting fluid from said zone.

45 9. In combination, a casing forming a condensing zone, means for delivering an annular series of solid jets of cooling water into said zone, a splitter in the path of each of said jets for dividing the same and for laterally spreading the divisions thereof within said zone, means for delivering steam against said jet divisions, and means for conducting fluid from said zone.

10. In combination, a casing forming an annular condensing zone, means for delivering an annular series of solid jets of cooling water radially into said zone, a vertical splitter in the path of each of said jets for dividing the same and for laterally spreading the divisions thereof within said zone, means for delivering steam against said jet divisions, and a converging wall for conducting fluid from said zone.

11. In combination, an annular casing

65 forming a condensing zone having a vertical axis, means for delivering an annular series of solid jets of cooling water horizontally into and toward the axis of said zone, a vertical splitter in the path of each of said jets for dividing the same and for laterally spreading the divisions thereof to form an annular series of vertical films of water within said zone, means for conducting steam downwardly through said zone and along said films of water, and means for 75 conducting fluid from a lower portion of said zone.

12. In combination, a casing forming an annular condensing zone and an annular conduit surrounding said zone, means for delivering 80 a series of solid jets of cooling water from said conduit into said zone, a splitter in the path of each of said jets for dividing the same and for laterally spreading the divisions thereof to form films of 85 water within said zone, means for delivering steam against said films of water, and means for conducting fluid from said zone.

13. In combination, a casing forming a condensing zone, means for delivering superposed annular series of solid jets of 90 cooling water into said zone, a splitter in the path of each of said jets for dividing the same and for laterally spreading the divisions thereof within said zone, means for conducting steam against said jet divisions, and 95 means for conducting fluid from said zone.

14. In combination, a casing forming an annular condensing zone, means for delivering superposed annular series of solid 100 jets of cooling water horizontally into and toward the center of said zone, a vertical splitter in the path of each of said jets for dividing the same and for laterally spreading the divisions thereof to form vertical 105 films within said zone, means for conducting steam downwardly along said jet divisions, and means for conducting fluid from the lower end of said zone.

15. In combination, a casing forming an 110 annular condensing zone and a plurality of annular conduits surrounding said zone, means for delivering cooling water to one of said conduits, means for delivering said cooling water from said conduit into said 115 zone, means for conducting elastic fluid from said zone into another of said conduits, and means for removing said elastic fluid from said other conduit at its uppermost portion.

16. In combination, a casing forming a condensing zone, means for delivering a plurality of jets of cooling fluid into said zone, a downwardly converging wall for conducting fluid from said zone, an annular 125 air pocket surrounding said wall, and conduit means located above said zone for conducting air from said pocket.

17. In combination, a casing forming a condensing zone, means for delivering a plurality of solid jets of cooling water into said zone, a splitter in the path of each of said jets for distributing the water within said zone, a downwardly converging wall for delivering fluid from said zone, an an-

nular air pocket surrounding said wall, and conduit means providing an air outlet from said pocket at the upper end of said zone. 10

In testimony whereof, the signature of the inventor is affixed hereto.

CHARLES M. YATES.
